(57) **CLAIM**

I, claim the ornamental design for a container for lip balm, as shown and described.

DESCRIPTION

FIG. 1 Is a front elevation view of a container for lip balm showing my new design;

FIG. 2 Is a top plan view thereof;

FIG. 3 Is a bottom plan view thereof;

FIG. 4 Is a bottom front perspective view of FIG. 1; and,

FIG. 5 Is an exploded front elevation view of FIG. 1.

The broken lines showing a lip balm product illustrate environmental structure that forms no part of the claimed design.
